UNITED STATES PATENT OFFICE.

MORRIS HOWE, OF DULUTH, MINNESOTA.

SUCTION BRACKET.

Application filed April 24, 1925. Serial No. 25,512.

To all whom it may concern:

Be it known that I, MORRIS HOWE, a citizen of the United States, residing at Duluth, in the county of St. Louis and State of Minnesota, have invented certain new and useful Improvements in Suction Brackets, of which the following is a specification, reference being had therein to the accompanying drawing.

- 10 This invention relates to portable supports or brackets, and has special reference to such a bracket designed to be suspended in position against a somewhat smooth surface by suction.
- 15 The object of the present invention is to provide such a device more efficient and practical than heretofore known, and one that is capable of being made more secure from time to time without altering its position.
- 20 Another object is to provide such a device, simple of release, and without injury to same.

Other objects and advantages of the invention will appear in the further description.

25 Referring now to the accompanying drawing, forming part of this application, in which like reference characters indicate like parts:

Figure 1 is a central vertical section 30 through one of the brackets as it would appear attached to a wall; and

Figure 2 is a fragmental side elevation of the light suspending band.

1 represents a sheet metal cylinder mounted 35 within a substantially frustro-conically shaped body portion 2, the base of which is considerably larger in diameter than the cylinder and the top fitting same snugly. A convex cap 3 covers the end of the cylinder 40 and is snugly attached to the end thereof forming a continuation of the upper or outer end of the cone 2 in appearance.

The base flange-like termination 4 of the cone is somewhat flared as at 5 and sur- 45 mounted by the rubber gasket 6, the same being somewhat enlarged about that portion into which the flare 5 of the flange 4 extends, the rim 7 of the gasket lying against the inner face of the flange 4 and there tightly 50 impinged by the expandible band 8, the opposite ends of which have lugs 9 formed thereupon with internally screw-threaded holes therein into which the bolt 10 is screw-threadedly mounted, said bolt intermediate 55 of the lugs 9 having a fixed squared portion or nut 11, and, being oppositely screw-

threaded upon the ends, that is to say, right and left hand threads, the band 8 is conveniently adjusted for insuring a tight joint intermediate of the gasket and the inside of 60 the body portion of the bracket.

As a reinforcing or bracing element for the inner end of the cylinder 1 I provide the dished brace 12 which is fastened at one end to the inner wall of the body portion 65 2 and the opposite end overlapping the end of the cylinder to which it is securely fastened by soldering or in any desired manner. This bracing member is perforated as shown at 13 so as to permit free access of air there- 70 through in order to maintain as large a chamber as possible within the bracket.

On the inner end of the cylinder 1 is formed a chamber 14 having an axial port 15 therein which is controlled by the valve 75 16, and there are ports 17 leading from the chamber 14 into the cylinder 1. This valve as is obvious may be of any desired structure.

Within the cylinder 1 is mounted a piston rod 18 carrying the piston 19 which is of 80 the common air pump construction, that is free to operate inwardly and function only as a suction device when drawn outwardly. On the outer end of the piston rod 18 is formed double looped portions 85 20 for convenient manipulation with two fingers. About the piston rod 18 is mounted a contractile spring 21 which is attached to the piston rod adjacent the piston 19 as at 22 and extending outwardly of the head 90 3 of the cylinder where it is attached as at 23, so that there is at all times a stress outwardly upon the piston, the object being to maintain as nearly as possible a uniform 95 suction within the bracket, such outward stress of the piston compensating for any insignificant leaks that might occur in the device.

About the outermost small end of the body portion 2 is mounted a light supporting 100 band or ring 24, there being a concaved seat about the exterior of the body portion for installation of same. This band is provided with opposed lugs 25 carrying a co- 105 operative thumb screw 26 by which the band may be tightened or loosened as desired about the extremity of the bracket.

Opposite the termini of the band are attached thereto similar spaced lugs indicated 110 at 27, and intermediate of which is pivotally mounted as at 28 one arcuately shaped arm 29, foldable when desired up against the

body portion 2. At the free end of this arm is pivotally mounted as at 30 a like arm 31 carrying upon its extreme end as at 32 the electric lamp 33. By this arrangement it is apparent that the lamp may be adjusted slightly to or from the bracket and may be placed in any desired position radially about the brackets.

From the foregoing it is apparent that 10 I have produced a suction bracket of very simple and practical construction and one that may be attached to a smooth flat surface with considerable force or pressure resulting upon the extent to which the pumping portion 15 of the device is operated, and one that may be readily adjusted. For the purpose of convenient release of the bracket when desired there is provided the plug 34 pivotally mounted as at 35 and controllable by 20 the handle 36 thereupon, the same being held normally closed by the spring 37 which keeps the plug 34 in the hole in the body portion 2.

Having thus described my invention, what 25 I claim and desire to secure by Letters Patent, is:

1. A suction bracket of the class described comprising an air pump, a housing attached to the base of the pump forming a chamber 30 communicating therewith, a resilient cushioning means about the free contacting edges of the housing, a piston within the

pump, and means whereby the piston normally tends to exhaust the chamber.

2. A suction bracket of the class described comprising an air pump, a substantially frusto-conically shaped casing surrounding the pump forming a chamber thereabouts, resilient surface contacting means about the base of the casing, a spring actuated piston 40 within the pump for normally maintaining the suction of the bracket, and means for supporting a lamp upon the bracket.

3. A suction bracket of the class described comprising an air pump, a substantially frusto-conically shaped casing surrounding the pump forming a chamber thereabouts, resilient surface contacting means about the base of the casing, a spring actuated piston 45 within the pump for normally maintaining the suction of the bracket, and means for adjustably supporting a lamp on the forward end of the bracket.

4. A suction bracket of the class described comprising an air pump, a substantially frusto-conically shaped casing surrounding the pump forming a chamber thereabouts, resilient surface contacting means about the base of the casing, means for supporting a lamp upon the bracket, and means for instantly releasing the suction of the bracket.

In testimony whereof I hereunto affix my signature.

MORRIS HOWE.
